UNITED STATES PATENT OFFICE.

ERIK HJALMAR FRISELL, OF STOCKHOLM, SWEDEN, ASSIGNOR, BY MESNE ASSIGNMENTS, TO HELGE AX:SON JOHNSON, OF STOCKHOLM, SWEDEN.

ADJUSTING MEANS FOR ORDNANCE.

1,086,590.

Specification of Letters Patent. Patented Feb. 10, 1914.

Application filed December 7, 1909. Serial No. 531,807.

To all whom it may concern:

Be it known that I, ERIK HJALMAR FRISELL, a subject of the King of Sweden, residing at Stockholm, in the Kingdom of Sweden, have invented a new and useful Adjusting Means for Ordnance, of which the following is a specification, reference being had to the drawing accompanying and forming a part hereof.

10 This invention relates to means for elevating and training ordnance mounted in carriages.

The object of the invention is to make it possible to scour an obliquely extending mark, *i. e.* a mark extending at an angle to the horizontal, or the vertical plane, or both.

15 The invention consists, chiefly, in that the trunnions, or the like, of the barrel are adjustable in a plane forming an angle, suitably a right angle, with the axis of the barrel. In other words, the trunnions are adapted to swing about the axis of the barrel, either by the trunnions being movable on the barrel or the barrel with the trunnions attached thereto being adapted to turn about its axis.

20 In the drawing, I have shown an elevating and training device embodying the invention.

25 Figure 1 is a longitudinal sectional view of the device, and Fig. 2 is rear view of the same (the barrel being removed).

30 Referring to the drawing, the barrel *a* is provided with an annular flange or collar *b* serving as a guide for a ring *c* which is adapted to be turned about the said flange and locked in position thereon. Attached to the ring *c* are trunnions *d*. These trunnions are journaled in a second ring *e* which is wide enough to allow the barrel with the ring *c* to be swung freely on the trunnions *d*. The ring *e* is adapted to be adjusted and locked in position within an outer ring or clamp *f* which is adapted to be swung laterally and to this end provided with a foot *g* supported by and adapted to be locked in position on the elevating arc *h*. The latter is supported in usual manner in the carriage and adapted to be turned about the axis *i*.

35 The described device is used in the following manner: When the barrel has been elevated by adjusting the arc *h* and trained by swinging the ring *f* and these two parts have been locked in position, the ring *e* is turned in the ring *f* until the trunnions *d*

take up the oblique position corresponding to the oblique extension of the mark to be scoured. The ring *e* is thereupon secured in position in the ring *f* and the barrel is turned in the ring *c* so that the parts mounted on the barrel (the sighting device, the firing mechanism, etc.) obtain the positions required for scouring the mark. The ring *c* is thereupon secured in position on the barrel and, when the latter is thereupon swung laterally, the elevation is continuously changed during swinging, *i. e.* the mouth of the barrel is raised and lowered during swinging corresponding to the position of the obliquely extending mark.

40 I claim:

1. In a gun, the combination of an outer ring, a second ring mounted in the said outer ring so as to be adjusted in a plane forming an angle with the axis of the gun, 75 and a barrel mounted on trunnions in the said second ring in such a manner as to be adjustable laterally therein.

2. In a gun, the combination of an outer ring, a second ring mounted in the said outer ring so as to be adjusted in a plane forming an angle with the axis of the gun, a third ring mounted on trunnions in the said second ring in such a relation thereto as to permit lateral adjustment therein, and a barrel adjustably mounted in the said third ring. 85

3. In a gun, the combination of an adjustably supported outer ring, a second ring mounted in the said outer ring so as to be adjusted in a plane forming an angle with the axis of the gun, and a barrel mounted on trunnions in the said second ring in such a manner as to be adjustable laterally therein. 90

4. In a gun, the combination of an adjustably supported outer ring, a second ring mounted in the said outer ring so as to be adjusted in a plane forming an angle with the axis of the gun, a third ring mounted on trunnions in the said second ring in such a relation thereto as to permit lateral adjustment therein, and a barrel adjustably mounted in the said third ring. 100

5. In a gun, the combination of an elevating arc, an outer ring supported by the said elevating arc, a second ring mounted in the said outer ring so as to be adjusted in a plane forming an angle with the axis of the gun, and a barrel mounted on trunnions in 110

the said second ring in such a manner as to be adjustable laterally therein.

6. In a gun, the combination of an elevating arc, an outer ring supported by the 5 said elevating arc, a second ring mounted in the said outer ring so as to be adjusted in a plane forming an angle with the axis of the gun, a third ring mounted on trunnions in the said second ring in such a relation thereto as to permit lateral adjustment 10 therein, and a barrel adjustably mounted in the said third ring.

7. In a gun, the combination of an elevating arc, an outer ring adjustably supported 15 in the said elevating arc, a second ring mounted in the said outer ring so as to be adjusted in a plane forming an angle with the axis of the gun, and a barrel mounted

on trunnions in the said second ring in such a manner as to be adjustable laterally 20 therein.

8. In a gun, the combination of an elevating arc, an outer ring adjustably supported in the said elevating arc, a second ring mounted in the said outer ring so as to be 25 adjusted in a plane forming an angle with the axis of the gun, a third ring mounted on trunnions in the said second ring in such a relation thereto as to permit lateral adjustment therein, and a barrel adjustably 30 mounted in the said third ring.

ERIK HJALMAR FRISELL.
